The United States of America.

To all whom these Letters Patents shall come:

WHEREAS John M. Henry, a citizen of the State of Massachusetts, aforesaid, of the United States, hath alleged that he has invented a new and useful improvement in gasoline and kerosene lamps for lighting; which improvement has not been known or used before his application; has adequately proved that he does really believe that he is the true inventor or discoverer of the said improvement; has paid into the Treasury of the United States, the sum of thirty dollars, delivered a receipt for the same, and presented a petition to the Secretary of State, praying a decree of obtaining an exclusive property in the said improvement, and praying that a patent may be granted for that purpose: These are therefore granted, according to law, to the said John M. Henry, his heirs, administrators, or assigns, for the term of fourteen years, from the twentieth day of April, in the year of our Lord, one thousand four hundred and thirty-four, of the Independence of the United States of America, the twentieth day of April, in the year of our Lord, one thousand four hundred and thirty-five, and exclusive right and liberty of making, constructing, using, and vending no others to be used, the said improvement, a description whereof is given in the words of the said Letters Patent, which are as follows:

In Testimony whereof, I have caused these Letters to be made Patent, and the Seal of the United States to be hereunto affixed.

Given under my hand, at the City of Washington, the twentieth day of April, in the Year of our Lord, one thousand four hundred and thirty-four, and of the Independence of the United States of America, the twentieth day of April,

By the President,

John C. Calhoun Secretary of State.

City of Washington. To wit:

THE HEREBY CERTIFY, That the foregoing Letters Patent, were delivered to me on the twentieth day of April, in the year of our Lord, one thousand four hundred and thirty-four, and are now in my possession, and are transmitted, that I have received the same, and that there corresponds to the same, and I do hereby return the same to the Secretary of State, within fifteen days from the date of their transmission to me. On the twentieth day of April, in the year of our Lord, one thousand four hundred and thirty-four.

John C. Calhoun

United States Patent

Patent No.: 246

The shareholders are to be given a choice of the shares or stock and shares of the company which are to be distributed among them.

1900-1901

United States Patent

Patent No.: 246